Inventor:

John A. Haase,

UNITED STATES PATENT OFFICE.

JOHN A. HAASE, OF PHILADELPHIA, PENNSYLVANIA.

RATCHET-DRILL.

SPECIFICATION forming part of Letters Patent No. 286,294, dated October 9, 1883.

Application filed July 3, 1883. (Model.)

To all whom it may concern:

Be it known that I, JOHN A. HAASE, a citizen of the United States, residing at No. 116 Vanhorn street, in the city and county of Philadelphia and State of Pennsylvania, have invented a new and useful Improvement in Hand Drilling-Machines for Drilling Metal; and I do hereby declare that the following is a full and exact description of the invention, reference being had to the accompanying drawing and to the letters of reference marked thereon.

My invention relates to machines, called "ratchet-drills," all of which have a single handle for revolving the drill when required. Such machines stop at every repeated stroke, the drill running half-time only, and this causes side strain or friction in large holes.

My machine for small holes (not requiring much labor) runs almost continuously, and while drilling large holes, by operating the two handles and running at the ordinary speed I avoid friction.

The drawing is a side view of the machine. A is the set (or extension) screw; B, spindle; C and C, ratchet-wheels; D and D, bodies; E and E, handles. In each body is a pawl,

(or catch,) which slides centrally to and fro and catches into the teeth of the ratchet-wheels, and a spiral spring in each body keeps the said pawls properly in place.

In use a device, commonly termed "old man," is clamped on the work to be drilled, which device is provided with a projecting arm for the point of set-screw A to bear against, thus forcing the drill that is placed in the other end of the spindle into the metal to be drilled.

I claim—

The combination, as herein described and shown, of the spindle B, two ratchet-wheels, C, rigidly connected thereto, and having teeth inclined in the same direction, two bodies, D, each containing a pawl and spring for holding the pawl and ratchet-wheel in contact, and two handles, E, rigidly connected to the said bodies.

In testimony that the above is my invention I have hereunto set my hand this 24th day of May, 1883.

JOHN A. HAASE.
